CLAIM

The ornamental design for a grip for robot hand, as shown and described.

DESCRIPTION

FIG. 1 is a front perspective view of a grip for robot hand showing our new design;

FIG. 2 is a rear perspective view thereof;

FIG. 3 is a front elevational view thereof;

FIG. 4 is a rear elevational view of an environmental structure in which the design is embodied;

FIG. 5 is a left side elevational view thereof;

FIG. 6 is a right side elevational view thereof;

FIG. 7 is a top plan view thereof;

FIG. 8 is a bottom plan view thereof;

FIG. 9 is a right side elevational view thereof in a first alternate position;

FIG. 10 is a top plan view thereof in the first alternate position;

FIG. 11 is a front perspective view thereof in the first alternate position;

FIG. 12 is a top plan view thereof in a second alternate position;

FIG. 13 is a front perspective view thereof in the second alternate position;

FIG. 14 is a right side elevational view thereof in the second alternate position;

FIG. 15 is an enlarged partial view of a region defined by lines **15-15** of FIG. 1; and,

FIG. 16 is a front perspective view thereof showing environmental structure in broken lines.

The broken lines in the drawings illustrate portions of the grip for robot hand that form no part of the claimed design. The dashed broken line border of the enlarged detailed view in FIG. 15 forms no part of the claimed design.
